UNITED STATES PATENT OFFICE.

EDWARD S. STIMPSON, OF HOPEDALE, MASSACHUSETTS, ASSIGNOR TO DRAPER COMPANY, OF PORTLAND, MAINE, AND HOPEDALE, MASSACHUSETTS, A CORPORATION OF MAINE.

THREAD-CUTTER FOR WEFT-REPLENISHING LOOMS.

No. 872,471.

Specification of Letters Patent.

Patented Dec. 3, 1907.

Application filed June 28, 1906, Serial No. 323,803.

To all whom it may concern:

Be it known that I, EDWARD S. STIMPSON, of Hopedale, in the county of Worcester and State of Massachusetts, have invented certain new and useful Improvements in Thread-Cutters for Automatic Weft-Replenishing Looms, of which the following is a specification.

In automatic weft-replenishing looms wherein weft is replenished prior to the complete exhaustion of the running weft, the outgoing weft-carrier still has weft on it which extends from it to the adjacent selvage of the cloth. It is important that this thread should be cut promptly since, otherwise, the spent weft is apt to be carried into the shed with the fresh weft, or, other troubles are likely to ensue.

The object of the present invention is to produce mechanism for cutting this outgoing spent weft quickly and certainly.

The present mechanism is illustrated in the accompanying drawings, in which—

Figure 1, is a plan view of so much of an automatic weft-replenishing loom as is necessary for an understanding of the present invention. Fig. 2, is a vertical section of the loom. Fig. 3, is a detail of the spent weft-cutter. Fig. 4, is a vertical section illustrating the action of the spent weft-catcher. Fig. 5, is a plan view of the spent weft-cutter.

A, is the breast-beam of the loom; B, is the lay; C, is the shuttle; and D, is the reciprocating temple at the change side of the loom which carries the thread-cutter for the fresh weft, said cutter being indicated at E. There is also shown in the drawings a usual starting-shaft F, which is rocked when the weft is to be replenished and by its rocking brings

into action the weft-replenishing mechanism. Certain usual parts are shown in connection with this starting-shaft. It is shown in Fig.

2, as provided with an arm a, which is operatively connected in a well-known way with

the usual shuttle feeler partly shown at G, and with a restoring-spring H. The shuttle feeler G, swings on pivot stud b, and it carries an arm c, (see Fig. 1) which immediately

controls a stud d, on the usual transference dog which governs the transference and hence the replenishment of weft. This stud d, sufficiently indicates the weft-replenishing mechanism. Associated with these known

parts are the parts which constitute the present improvement.

The spent weft-cutter is located between the temple and the selvage held by it and the shuttle box at the change end of the lay, and acts upon the spent weft close to the plane of the point of the shuttle when occupying the shuttle-box at the change end of the lay. It is composed of a stationary blade I, and a movable blade J. Both of these blades are carried by a stationary part of the loom in front of the lay. The movable blade has a depending finger e, and the two blades are held apart as illustrated in Fig. 3, by means of a spring f, interposed between this finger and a fixed socket. The movable blade is moved to close and cut any thread located between it and the stationary blade by the lay, or a part carried thereby, striking the finger e. Any other means can be employed for closing the movable blade as the loom operates. It is convenient, however, to have the closing movement effected by the lay or a part carried thereby. The movable blade swings on a fixed pivot stud g, (see Fig. 5), and a spring h, maintains the movable blade in cutting contact with the fixed blade I. This spent weft-cutter is forward of the path of the weft extending from the adjacent selvage to the adjacent shuttle-box so that it cannot cut the running weft. In order that it may cut the spent weft, a thread catcher and carrier K, is employed, which performs its functional movements only when the weft-replenishing mechanism acts. This thread catcher and carrier K, is supported at its forward end upon fixed horizontal rod L, and a spring M, surrounding said rod and acting upon the forward end of the thread catcher and carrier, maintains said thread catcher and carrier normally in its forward position out of reach of the running weft. The connection between the thread catcher and carrier and the rod L, is a loose one, permitting the thread catcher and carrier to swing freely up and down. The thread catcher and carrier is supported at its middle upon an actuator N. This actuator has a bowl i, upon which the thread catcher and carrier rests, said thread catcher and carrier having an open mouthed recess m, for this purpose. The actuator N, is pivoted at i, and it has an elongated slot O, into which enters a stud P, carried by a crank arm Q, which is fast on the hub of the shuttle feeler G.

The lay B, has a recess R, in line with the thread catcher and carrier, this recess being

open at the top and extending below the race-way of the lay. This recess extends the entire width of the lay. Back of this recess the lay carries a releasing cam S, which is adapted 5 to act upon the rear end of the thread catcher and carrier to disconnect it from the actuator. The thread catcher and carrier at its rear is provided with a forwardly and upwardly projecting catch T, and with a rearwardly and upwardly extending guard U, the two arms forming between them and above the body of the thread catcher and carrier a triangular recess open at its upper rear part. Normally, the actuator N, occupies the position shown in Fig. 2, being held therein by the spring H, and with its upper end resting against the breast-beam. When the condition of the running weft demands replenishment, the starting-shaft 20 F, is rocked, elevating the arm a, and thereby swinging the shuttle feeler G, toward the then approaching lay. This movement of the shuttle feeler carries with it the attached crank arm Q, which through its stud P, acting in the slot O, of the actuator N, swings said actuator rearwardly to the position shown in Fig. 4. This movement of the actuator carries the thread catcher and carrier K, backwardly to the position shown in 30 Fig. 4, and puts the spring M, under compression. As the result of the relative approach of the lay and of the thread catcher and carrier the rear end of said thread catcher and carrier enters the recess R, of the lay and 35 in so doing the rear end of the thread catcher and carrier is carried beneath the spent weft and said weft occupies the triangular recess constituted by the catch T, and guard U. As the lay continues its forward movement, 40 the releasing cam S, encounters the rear end of the thread catcher and carrier as is indicated in Fig. 4. Still further forward movement of the lay lifts the rear end of the thread catcher and carrier so that the spent 45 weft is caught by the catch T; and this elevation of the thread catcher and carrier continues until it is entirely freed from the bowl i, of the actuator, whereupon the spring M, almost instantaneously, restores the thread 50 catcher and carrier to its original forward position. This forward movement of the thread catcher and carrier is more rapid than the forward movement of the lay so that the thread catcher and carrier brings the spent 55 weft between the still open blades of the spent weft-cutter before the lay strikes the finger e, of the movable blade. The spent weft being thus in position between the two blades, the cutter is actuated by the lay and 60 the thread is cut. The spent weft is cut approximately as the lay is at front center at which time the transerrer acts to discharge the spent weft-carrier and insert a fresh one. As the spent weft is then cut, the spent weft-carrier in its discharge carries with it the

thread still held by it. When the weft-replenishment has been completed, the shuttle feeler G, and actuator N, are restored to their normal positions by spring H, and the bowl i, resumes its position in the recess R, of the thread catcher and carrier.

The stand W, which carries the spent weft-cutter has an elastic spring guard X, which overhangs the thread catcher and carrier K, (see Fig. 1) so as to afford a yielding 75 surface to limit the upward movement of the thread catcher and carrier when it is thrown upwardly by the cam S.

A thread guide V, adjacent the fixed cutting blade (see Figs. 3, and 5), insures the 80 entrance of the spent weft between the two cutting blades. Also, a thread guide Z, (see Figs. 1, and 2,) is carried by the temple D, so that the spent weft may not be carried above the temple by the action of the thread 85 catcher and carrier. This leaves the end of the spent-weft adjacent the temple in position to be cut close to the selvage by the usual temple thread-cutter E, the primary office of which is to cut the fresh weft.

The thread catcher and carrier lies close to the stand W, and hence when it returns to its forward position the thread carried by it is caught between it and the stand, so that the thread is properly held to be cut by the 95 temple thread cutter E. The short end of thread then held is dropped at the next reciprocation of the thread catcher and carrier.

I claim as my invention:—

1. An automatic weft-replenishing loom in which the weft is replenished before complete exhaustion having, in combination, a spent weft-cutter mounted on a stationary part of the loom in front of the lay, said cutter having a movable blade which is actuated regularly during the running of the loom, and means for bringing a weft thread extending from the adjacent selvage to the adjacent shuttle-box within reach of the said cutter, said means being brought into action when the weft-replenishing mechanism is brought into action.

2. An automatic weft-replenishing loom in which the weft is replenished before complete exhaustion having, in combination, a spent weft-cutter mounted on a stationary part of the loom in front of the lay and between the shuttle box at the replenishing side of the loom and the adjacent temple, said cutter having a movable blade which is actuated regularly during the running of the loom, and means for bringing a weft thread extending from the adjacent selvage to the adjacent shuttle-box within reach of the spent weft-cutter.

3. An automatic weft-replenishing loom in which the weft is replenished before complete exhaustion having, in combination, a spent weft-cutter mounted on a stationary

part of the loom in front of the lay and adapted to cut the spent weft close to the plane of the point of the shuttle when occupying the shuttle-box at the change end of the lay, and 5 means for bringing a weft thread extending from the adjacent selvage to the adjacent shuttle-box within reach of said cutter, said means being brought into action when the weft-replenishing mechanism is brought into 10 action.

4. An automatic weft-replenishing loom in which the weft is replenished before complete exhaustion having, in combination a spent weft-cutter mounted on a stationary 15 part of the loom in front of the lay and adapted to cut the spent weft close to the plane of the point of the shuttle when occupying the shuttle box at the change end of the lay, and means located between said cutter 20 and the adjacent selvage for bringing a weft thread extending from the adjacent selvage to the adjacent shuttle-box within reach of said cutter.

5. An automatic weft-replenishing loom 25 in which the weft is replenished before complete exhaustion, having, in combination, a cutter for the fresh weft, and a second cutter for the spent-weft mounted on a stationary part of the loom in front of the lay, and 30 means for bringing a weft thread extending from the adjacent selvage to the adjacent shuttle-box within reach of said second cutter.

6. An automatic weft-replenishing loom 35 in which the weft is replenished before complete exhaustion, having, in combination, a lay having a recess below the raceway; a spent weft thread-cutter mounted upon a stationary part of the loom in front of the 40 lay and between the adjacent selvage of the cloth and the shuttle-box at the change side of the loom, said thread-cutter comprising a movable blade which is positively actuated by the lay regularly during the running 45 of the loom; a normally stationary thread catcher and carrier in front of the lay and in line with said lay-recess, having means for catching the spent weft; a cam carried by the lay back of said recess for acting on the 50 rear end of the thread catcher and carrier; an actuator for said thread catcher and car-

rier which is brought into action at the time that the weft - replenishing mechanism is brought into action, said actuator acting to move the thread catcher and carrier rearwardly toward the approaching lay, said thread catcher and carrier then entering the recess of the lay and being encountered by the cam on said lay, whereupon it is released from the actuator; and a spring acting on 60 said thread catcher and carrier to throw it quickly forward when released from the actuator by the cam on the lay.

7. An automatic weft-replenishing loom in which the weft is replenished before complete exhaustion, having, in combination, a spent weft thread-cutter mounted upon a stationary part of the loom in front of the lay and between the adjacent selvage of the cloth and the shuttle-box at the change side, 70 of the loom; a normally stationary thread catcher and carrier in front of the lay having means for catching the spent weft; an actuator for said thread catcher and carrier which is brought into action at the time that the weft-replenishing mechanism is brought into action as the result of the approaching exhaustion of the running weft, said actuator acting to move the thread catcher and carrier rearwardly toward the approaching lay, 75 to catch the spent weft; and means acting on said thread catcher and carrier to throw it forward ahead of the lay and to bring the caught thread within the sphere of action of said cutter.

8. An automatic weft-replenishing loom in which the weft is replenished before complete exhaustion having, in combination, a spent weft-cutter having a movable blade which is actuated regularly during the running of the loom, and a thread catcher and carrier which brings a weft thread extending from the adjacent selvage to the adjacent shuttle box within reach of said cutter.

In witness whereof, I have hereunto signed 95 my name in the presence of two subscribing witnesses.
